A. PETERSON.

SHOE FASTENER.

APPLICATION FILED MAY 9, 1917.

1,256,254.

Patented Feb. 12, 1918.

UNITED STATES PATENT OFFICE.

ARCHIE PETERSON, OF LOS ANGELES, CALIFORNIA.

SHOE-FASTENER.

1,256,254.

Specification of Letters Patent. Patented Feb. 12, 1918.

Application filed May 9, 1917. Serial No. 167,48.

To all whom it may concern:

Be it known that I, ARCHIE PETERSON, a citizen of the United States, residing at Los Angeles, in the county of Los Angeles and State of California, have invented certain new and useful Improvements in Shoe-Fasteners, of which the following is a specification.

This invention relates to an improved shoe fastener and has as its primary object to provide an arrangement wherein the shoe lace may be easily and quickly loosened for removing the shoe and may be as easily secured when putting on the shoe.

The invention has as a further object to provide a construction employing a lacing flap for securing the uppermost loops of the lace at one side of the upper so that this flap may be released for loosening the lace sufficiently to permit the removal of the shoe without the necessity of unlacing the shoe and wherein the said flap may be readily secured in position for lacing up the shoe without the necessity of passing the shoe lace through the uppermost eyelets of the shoe.

And the invention has as a still further object to provide a fastener which will be neat and attractive in appearance and which may be readily employed upon substantially any conventional type of shoe.

Other and incidental objects will appear as the description proceeds and in the drawings wherein I have illustrated the preferred embodiment of the invention and wherein similar reference characters designate corresponding parts throughout the several views:

Figure 1 is a perspective view showing a shoe equipped with my improved fastener;

Fig. 2 is a fragmentary perspective view showing the arrangement of the eyelets at opposite sides of the upper extremity of the upper of the shoe;

Fig. 3 is a detail perspective view of the lacing flap employed;

Fig. 4 is a sectional view showing the manner in which the lacing flap is engaged with the upper for lacing up the shoe;

Fig. 5 is a detail perspective view showing the lace detached.

In order that the construction, mounting and operation of my improved fastener may be accurately understood, I have, in the drawings, shown the device in connection with a conventional type of shoe 10 having

an upper formed with sides 11 and 12. In carrying out the invention, I secure to the side 11 of the upper, adjacent the front opening therein, a plurality of eyelets 13 arranged in alinement. Connected to the opposite side 12 of the upper, adjacent the said opening, are a plurality of eyelets 14 which are also arranged in alinement. The eyelets 14 are similar to the eyelets 13 and are arranged at the lower extremity of the said side of the upper. Disposed above the row of eyelets 13 is a row of eyelets 15 which, as particularly shown in Fig. 2 of the drawings, are offset with respect to the row of eyelets 14. The purpose of this arrangement will presently appear.

Connected with the lowermost eyelet 14 is a lace 16. This lace may be formed of leather or other approved material and is provided, at the adjacent terminal thereof, with a suitable hook 17 engaging in the said eyelet. From the lowermost eyelet 14, the lace 16 is carried through the lowermost eyelet 13 to form a loop between the said eyelets and is then looped back and forth as particularly shown in Fig. 1 between the eyelets 13 and 14 until the lace has been carried through the uppermost eyelet 14 and a corresponding oppositely disposed eyelet 13. From this eyelet 13, the lace is then passed through the lowermost of a plurality of eyelets 18 carried by a lacing flap 19. This flap may be formed of leather or other approved material and is of a length substantially equal to the row of eyelets 15. As particularly shown in Fig. 3 of the drawings, the eyelets 18 are arranged in a row upon the flap adjacent one margin thereof and mounted in a row upon the opposite margin of the flap to project laterally therefrom are a plurality of hooks 20 arranged opposite the eyelets 18 and corresponding in number to the number of the eyelets 13. Extending from the inner edge of the flap 19 is a tab 21 and extending from the outer edge of the said flap are a plurality of tabs 22.

It is now to be observed that the eyelets 18 in the flap 19 are spaced apart to correspond to the spacing of the eyelets 13 in the side 11 of the upper of the shoe so that after the lace 16 has been passed through the lowermost of the eyelets 18 in the flap, the said lace may, as illustrated in Fig. 1, be looped back and forth between the eyelets 13 and 18 for connecting the flap with the

lace. These uppermost loops of the lace which are thus engaged with the flap 19 will consequently be free at corresponding ends thereof with respect to the side 12 of the upper of the shoe. For anchoring the said loops of the lace, the hooks 20 of the said flap are, as particularly shown in Fig. 4, engaged in the eyelets 15 and for drawing the flap to position over the said eyelets, the tabs 22 are provided upon the flap so that the flap may be easily grasped by the said tabs. After the flap has been moved to position the hooks 20 over the eyelets 15, the tab 21 may then be grasped for shifting the flap to engage the hooks within the said eyelets. With the upper end of the lace free, the hooks 20 of the flap 19 may thus be easily engaged with the eyelets 15 for simultaneously anchoring all of the uppermost loops of the lace to the side 12 of the upper of the shoe and it will now be noted that the row of eyelets 15 is offset with respect to the row of eyelets 14 a distance corresponding to the distance between the row of eyelets upon the flap 19 and the row of hooks 20. Therefore, with the hooks engaged within the row of eyelets 15, the eyelets 18 of the flap will be held in alignment with the row of eyelets 14 to thus maintain the uniformity in the appearance of the eyelets at opposite sides of the opening in the upper. Furthermore, this arrangement will, of course, tend to enhance the attractive appearance of the fastener.

From the uppermost eyelet 18, the upper end of the lace is carried across the flap 19 and around the side 12 of the upper to be adjustably secured by a locking clamp 23 arranged in the rear of the upper. Accordingly, after the flap 19 has been secured in place, the upper extremity of the lace may be drawn to tighten up the lace when by securing the free end of the lace by the clamp 23, the shoe will be securely fastened.

Furthermore, since the free end of the lace is arranged to overlie the flap 19, such free end of the lace will act to lock the flap 19 in position to thus reduce to a minimum the possibility of the accidental displacement of the said flap.

It will therefore be seen that I provide a particularly simple and efficient construction for the purpose set forth. To unfasten

the shoe, it is simply necessary to release the free end of the lace when by disengaging the flap 19, the uppermost loops of the lace will be freed to free the sides of the upper of the shoe so that the shoe may be easily and quickly removed. In like manner, the flap 19 may be engaged with the side 12 of the upper for simultaneously securing all of the uppermost loops of the lace when by drawing up upon the lace, the shoe may be readily fastened.

Having thus described the invention, what is claimed as new is:

1. In a fastener for shoes, the combination of a lace looped back and forth between the sides of the upper of the shoe, a lacing flap connected to the lace for anchoring the uppermost loop of the lace to one side of the shoe upper, and means for securing the free extremity of the lace to overlie the flap for locking the flap in position.

2. The combination with a shoe, and a plurality of eyelets arranged at opposite sides of the front opening therein, the uppermost eyelet at one side of the upper of the shoe being offset with respect to the intermediate eyelets upon the said side of the upper, of a fastener for the shoe including a lace looped back and forth between the sides of the upper through the said eyelets, a lacing flap provided with an eyelet having the uppermost loop of the lace passed therethrough, means carried by the flap and engageable in the offset uppermost eyelet of the said side of the upper for securing the uppermost loop of the lace to the said side of the upper with the eyelet of the flap arranged in alignment with the intermediate eyelets upon the said side of the upper, and means for securing the free end of the lace.

3. A fastener for shoes including a lace looped back and forth between the sides of the upper of the shoe, a lacing flap connected to the uppermost loop of the lace, means carried by said flap and arranged for engagement with one side of the shoe upper for securing the said loop of the lace to the upper at the said side thereof, a tab projecting from said flap and adapted to be grasped for manipulating the flap, and means for securing the free end of the lace.

In testimony whereof I affix my signature.

ARCHIE PETERSON. [I.S.]
